Dear Mr. Coops,
Charles W. Coops,
by Grosby & Gregory
attys.

UNITED STATES PATENT OFFICE.

CHARLES W. COOPS, OF TAUNTON, MASSACHUSETTS, ASSIGNOR TO COOPS MANUFACTURING COMPANY, OF BOSTON, MASSACHUSETTS, A CORPORATION OF MASSACHUSETTS.

CARRIAGE-TOP.

No. 891,815.

Specification of Letters Patent.

Patented June 30, 1908.

Application filed November 13, 1905. Serial No. 287,034.

To all whom it may concern:

Be it known that I, CHARLES WILLIAM COOPS, a citizen of the United States, and a resident of Taunton, in the county of Bristol 5 and State of Massachusetts, have invented an Improvement in Carriage-Tops, of which the following description, in connection with the accompanying drawing, is a specification, like letters on the drawings representing like parts.

This invention has for its object the improvement of tops for carriages whereby the bows will not cut the top when down.

As now commonly made when the top of a carriage is down the material used for covering the top is folded and enters between the bows, and the latter, as the carriage is being run, jump and move laterally, and by rubbing the material wear holes therein.

To obviate wearing holes in or marring the material forming the covering for the top, I have provided the bows with devices that not only prevent the contact of the bows when the top is down but which also aline 25 the bows and prevent any lateral vibration of one bow with relation to the other bows.

The devices for separating and alining the bows also stiffen the top so that any blow on the top is borne by all the bows.

Figure 1 shows part of an automobile or carriage body with the top down; Fig. 2 shows the bows and bow holders enlarged; Fig. 3 is an enlarged sectional detail showing the device for separating and alining the bows; Fig. 4 is a face view of the socket, Fig. 3, detached; Fig. 5 shows a modification, and Fig. 6 shows a cross-section of Fig. 5.

The top A; Fig. 1 is shown as down, and as pivoted on a stand A', secured to the body B 40 at opposite sides of the rear seat. When the top is raised, the nut a' is detached, the two front bows are carried forward and the free end of the lower end of the bow-holder c' is mounted on the stand B' fast on the body at 45 the sides of the front seat.

The top comprises as shown four top-holders c, c', c'', c''', at opposite sides of the body, each holder having a wooden bow, the latter being partially shown and designated 50 by the letters d, d', d'', d'''.

The bowholder c''' is jointed at 2 with the ear 3 of the bow holder c'', constituting the main bow-holder, it having an extension 4 pivoted at 5 on the stand A'. Bow holder c''

has another ear 6 on which is pivoted at 7 55 the bow holder c', while the bow-holder c is pivoted to an ear 8 extended from the bow-holder c'.

The threaded projections constituting the pivots referred to each receive a nut as a, a', 60 a'', a''', so that by removing any nut, any bow holder may be removed from the ear on which it is pivoted.

The parts so far specifically described are and may be all as usual with the exception of 65 the shape of the bow-holder which I will now describe.

Between the sides of the bows I have located devices to prevent the side edges of the bows from contacting one with the other, and also for alining said bows, and preventing any lateral shifting or sliding of the bows one with relation to the other. These devices as I have chosen to illustrate the same, Figs. 2, 70 3 and 4 comprise a socket e having suitable ears for the reception of screws by which to attach the socket to the bow at the point desired. Each socket is provided with a buffer e' shown as a piece of india rubber or other suitable non-metallic material.

The edge of the adjacent bow as d'' is provided with a block e'' having ears provided with holes for the reception of screws by which to attach the device to the bow, as shown in Fig. 3, said device having a projection 17 or being shaped as shown in Fig. 3 to enter the socket.

The device e, e'' serves two purposes, one as a stop to prevent contact of the bows one with the other, and also to aline and prevent 90 any lateral movement of the bows or bow-holders.

When the bows do not contact the material covering the top, which may be leather, cannot be pinched between the bows when 95 the top is down, nor can the bows move or shake sidewise one with relation to the other, and consequently the material of the top is not so pinched and rubbed that a hole is worn therein.

The alining of the bows at the top and so holding them that they cannot move laterally makes the top when down much more rigid, and any blow on the side of the top when down is resisted by all the bows.

Preferably the device e, e'' will be put all in the same line crossing the entire series of bows, as shown in the drawing, Fig. 2.

It is unnecessary to show any of the top covering as the same will be all as usual. As the devices e ; e^2 are operative only when the top is down, it is considered unnecessary to 5 illustrate the top as up.

The buffers absorb the shock of putting the top down and prevent the contact of metal with metal and does away with noise.

Fig. 5 shows the socket f and projection f' 10 of slightly different shape, that is, instead of the socket and projection being substantially circular, they are oblong.

Fig. 6 is a section on the line 8—8, Fig. 5, and it will be seen that the buffer f^2 has 15 wings f^3 . With the devices shown it is impossible for a bow to become marred when the top is down.

Having fully described my invention, what I claim as new and desire to secure by Letters 20 Patent is:—

1. In a carriage top, a bow having a socket provided with a buffer, and an adjacent bow having a projection entering said socket.

2. In a carriage top, a bow having a 25 socket, and an adjacent bow provided with a projection entering said socket and serving to aline the bows and prevent lateral movement of one bow with relation to another bow.

3. In a carriage or automobile top, a plurality of bows, and spacing devices carried by adjacent bows and adapted to space one from the other when the top is folded, the spacing device on one bow adapted to interlock with one on an adjacent bow. 30

4. In a top or canopy for a vehicle the combination with a plurality of jointed side arms of the bows, of stops on the facing sides of the arms, one having a socket and the next one provided with a projection to interlock 40 into said socket when the arms assume proximate relations.

5. In a top or canopy for a vehicle, the combination with a plurality of jointed side arms of the bows, of stops on the facing sides 45 of the arms, one having a socket made outwardly flaring, and the next one provided with a tapered projection to engage in said flaring socket when the arms are in their closed relations. 50

In testimony whereof, I have signed my name to this specification, in the presence of two subscribing witnesses.

CHARLES W. COOPS.
